RANGE OIL BURNER

Samuel J. De Flumere and Michael J. De Flumere,
Revere, Mass.

Application June 30, 1934, Serial No. 733,164

4 Claims. (Cl. 158—87)

Our invention relates to oil burners and particularly to the type of burner adapted for use in household ranges.

In the burner of this character commonly in use, the heat is generated in concentric combustion chambers generally including two burner units, and the heat from each combustion chamber, rising, heats the top of the stove unevenly in concentric areas over the chambers, the areas 5 between and at the ends being heated by conduction of the heat through the metal. Moreover the water back is inadequately heated, as each burner unit radiates the heat to the water back, from a maximum in a plane normal to the surface of the waterback and passing through the axes of the burners, varying in either direction to a minimum between burners and at the ends of the fire box.

One object of our invention is to provide a burner that will more uniformly heat the entire area of the stove top above the fire box, and at the same time radiate a uniform heat to the water back.

A second object is to provide a burner from which the carbonized oil may be readily removed, not only from the burner proper but from the heating chamber from which the oil is supplied to each combustion chamber.

A further object is to provide a heating chamber having independent connections to each combustion chamber.

Our invention consists in the novel construction of the burner base and the combustion chambers and the arrangement of a plurality of combustion chambers to deliver an approximately uniform heat to the stove top and the water back. Other novel features will appear in the accompanying specifications and claims and the drawing forming a part thereof.

We do not confine ourselves to the particular embodiment described and shown herewith, as modifications may be made within the scope of the appended claims.

In the drawing,

Fig. 1 is a sectional elevation substantially on the lines 1—1, of Fig. 2.

Fig. 2 is a plan view of a preferred embodiment of our invention with parts broken away to feature certain parts.

Fig. 3 is a sectional end elevation, substantially on the lines 3—3, Fig. 2.

Fig. 4 is a plan view of one form of burner stand having means for adjusting the burner in the fire pot.

In the drawing we have shown and have described a form in which two series of burners are

disposed on opposite sides of a median line and each series connecting with independent heating chambers, but we may use a single series connecting each burner with a single heating chamber, all having the essential features herein described and shown.

Referring to the drawing, 10 is a burner base having supporting means including the post 11, and the stand 12, and an eccentric sleeve 13 through which the post extends and is held in 10 adjusted position vertically by a set screw 14. The set screw 15 secures the sleeve in some laterally adjusted position of the burner base. No claim for novelty is made on this supporting means and other well known means may be substituted.

The plate 10 is substantially rectangular in outline and formed on its upper surface with a plurality of elongated troughs 16, having walls parallel to two sides of the plate and to each other and connected at their ends. Combustion chambers formed with perforated walls 18, extend upwardly from each trough and are supported by the walls thereof, the chambers alternating with air spaces 20 between combustion chambers. The 25 walls 18 are formed from sheet metal commonly used in oil burners, the perforations being indicated in part in Fig. 1.

The cover 21 is formed with slots 22 over each combustion chamber, and is supported by the 30 walls of the several combustion chambers.

In this embodiment we have shown two series of troughs and combustion chambers disposed in their elongated dimension normal to a median line across the plate, each series of troughs being 35 independently connected by ducts 220 with respective oil preheating chambers 23, 24, the wall 25 separating the chambers.

Each chamber is provided with independent inlets 26, 27 through which oil may be supplied 40 from a source of supply through the usual connections. Each chamber is provided at each end with openings 30, 31 through which access may be had for cleaning the chambers of sediment or carbonized oil, the plugs 28, 29 serving as closures 45 to the openings.

The oil entering the chambers spreads in a film as it passes to the ducts connecting the several burners, and when the burners are operating, the radiated heat raises the temperature of the walls 50 of the preheating chambers and is transmitted to the inflowing oil, raising its temperature to or near the vaporizing point before entering the troughs. In the embodiment shown, either series of burners or combustion units may be operated 55

by the usual arrangement of piping and needle valves to admit oil to one or both heating chambers.

With our burner, a greater proportion of the heat from the units contiguous to the water back is radiated uniformly to heat the walls of the water back, and at the same time a more uniform heating of the top of the stove is possible as well as the front wall of the range oven.

10 Having thus described our invention, we claim:—

1. An oil burner comprising a base plate formed with a plurality of independent elongated fuel troughs of substantially rectangular outline, and in parallel relation; perforated walls extending upwardly from and supported by the walls of respective troughs, and forming independent parallel combustion chambers separated by air spaces; a heating chamber formed in the plate and having individual duct connections to each trough and an inlet through which fuel oil may flow from the source of supply.
2. An oil burner comprising a base plate formed with a plurality of independent elongated fuel troughs of substantially rectangular outline, and in parallel relation; perforated walls extending upwardly from and supported by the walls of respective troughs, and forming independent parallel combustion chambers separated by air spaces; a heating chamber formed in the plate and extending across normal to the median lines of the troughs and having individual duct connections to each trough and an inlet through which fuel oil may flow from a source of supply.

3. An oil burner comprising a base plate of substantially rectangular outline, and formed with a plurality of independent elongated fuel troughs in parallel relation to opposite sides of the plate; perforated walls extending upwardly from and supported by the walls of respective troughs, and forming independent parallel combustion chambers separated by air spaces; a heating chamber formed in the plate and extending across normal to the median lines of the troughs and having individual duct connections to each trough and an inlet through which oil may flow from a source of supply.

4. An oil burner comprising a base plate of substantially rectangular outline, and formed with a plurality of elongated fuel troughs in parallel relation to opposite sides of the plate, and in series on either side of a median line across the plate; perforated walls extending upwardly from and supported by the walls of respective troughs, and forming parallel combustion chambers separated by air spaces; and oil preheating chambers formed in the plate and extending thereacross normal to the median lines of the troughs and separated from one another by a partition wall to form two compartments separating each series of troughs, each compartment having duct connections with each trough in the respective series of combustion chambers thereadjacent, said preheating chambers each having an inlet through which oil may flow from a common source of supply.
